UNITED STATES PATENT OFFICE.

FREDERICK L. MCGAHAN, OF LOS ANGELES, CALIFORNIA; VIOLA K. WALKER, ADMINISTRATRIX OF SAID FREDERICK L. MCGAHAN, DECEASED, ASSIGNOR TO THE PURPOSED MIND DEVELOPMENT SECURITY ASSOCIATION OF THE WORLD, A TRUST COMPANY.

MEANS FOR REUTILIZING STEAM.

Application filed June 16, 1919. Serial No. 304,454.

To all whom it may concern:

Be it known that I, FREDERICK L. MCGAHAN, a citizen of the United States, residing at the city of Los Angeles, in the 5 county of Los Angeles and State of California, have invented certain new and useful Improvements in Means for Reutilizing Steam, of which the following is a specification.

10 This invention is for subject-matter disclosed but not claimed in the application of the same inventor for patent for locomotive, 1,292,399, dated January 21, 1919, and relates more particularly to means governing 15 the admission of steam into the turbine from the ordinary driving mechanism of the locomotive or of shutting off the same.

For a complete understanding of the invention reference is to be had to the following description and the accompanying drawings in which:

20 Fig. 1 is a side elevation of a locomotive of the type shown in my prior Patent No. 1,292,399, the turbines and some of the connections thereto being shown by dotted lines,

25 Fig. 2 is a section through the smoke box of the locomotive and shows the passages for the steam to the driving engines of the locomotive and for the exhaust steam therefrom to the turbine that operates the suction fan,

30 Fig. 3 is a longitudinal sectional view of the turbine and suction fan driven thereby, and

35 Fig. 4 is a diagrammatic view of the locomotive engines and the turbine that drives the suction fan and the steam passages therebetween.

40 Referring to the drawings, it will be seen that the steam generated in the boiler 1 is supplied through the divider 2 (see Fig. 2) to the locomotive driving engines 5 by way of pipes or passages 3 and 4 to 45 the steam chests 5^a. The steam exhausts from the engines 5 into the passages 8 and 9 controlled by valves 16 and 17, shown more clearly by Fig. 2, and from these passages the exhaust steam passes by way of 50 the pipes 10 into the turbine 11, shown in detail by Fig. 3. The connections between the engines 5, valve controlled passages 8 and 9, and turbine 11 are shown diagrammatically by Fig. 4. Valves 16 and 17 are

55 mounted on valve rods 20 and are operated by reach rods, not shown, from the cab, through levers 19, as will be readily understood.

As described by my patent above referred to, No. 1,292,399, the turbine 11 is actuated 60 by the steam that impinges on the cone 13 being thereby driven together with the shaft 14 to which is fixed at one end the pinion 24 and at the opposite end the fan 23. The turbine thus acts as an auxiliary driving 65 means for the locomotive and also actuates the fan 23 to create a suction in the smoke box of the locomotive and, through the fire tubes that communicate between the smoke box and the fire box in the usual way, the 70 suction is communicated to the fire box and in this way fuel is drawn into the fire box and smoke, cinders and other products of combustion are drawn from the fire box through the pipes 25 into the turbine 11 75 where steam that passes into the turbine through the pipes 10 mixes therewith and exhausts from the turbine through the pipes 33. The structure just described is more completely described in my prior 80 patent and, as it forms no part of the invention claimed in this application, further description thereof is unnecessary.

The operation of the turbine 11 will be clearly understood from the above description. It will be seen that means is provided for supplying exhaust steam from the locomotive engines 5 on each side of the locomotive to the turbine 11 by way of passages 8 and 9 which are connected to 90 the pipes 10 that lead to the turbine 11. The passages 8 and 9 are controlled by valves 16 and 17, as previously described and in this way the turbine 11 can be put into and out of operation.

Having thus described my invention, what I claim is:

1. In combination with the driving engines of a locomotive, a turbine and means for supplying exhaust steam from the driving engine on each side of the locomotive to said turbine, said means comprising a plurality of passages, each passage constituting connection between a locomotive engine and the turbine.

2. In combination with the driving engines of a locomotive, a turbine for auxiliary power purposes, a valve casing having

95

100

105

valves therein, connections between the engines and the casing, and connections between the casing and the turbine, whereby exhaust steam from the engines of the locomotive may be supplied to the turbine through said casing and passages.

3. In combination with the engines on each side of a locomotive, a turbine for auxiliary power purposes, a valve casing, con-

nnections from the engines on each side of the locomotive with said valve casing, and connections from the valve casing to the turbine, whereby steam from the locomotive engines may be supplied to the turbine.

In testimony whereof I hereunto affix my signature.

FREDERICK L. McGAHAN.
